UNITED STATES PATENT OFFICE.

WILLIAM H. SILVER, OF NEW YORK, N. Y., ASSIGNOR TO THE SILVER & COMPANY, OF SAME PLACE.

AUTOMATIC OIL-STOVE.

SPECIFICATION forming part of Letters Patent No. 624,880, dated May 9, 1899.

Application filed January 16, 1899. Serial No. 702,228. (No model.)

To all whom it may concern:

Be it known that I, WILLIAM H. SILVER, a citizen of the United States of America, and a resident of the borough of Brooklyn, in the city and State of New York, have invented a new and useful Improvement in Automatic Oil-Stoves, of which the following is a specification.

This invention relates to automatic or self-regulating oil-stoves in which the oil is automatically fed to the burner with the requisite regularity, including provision for flooding the burner to facilitate lighting it and for draining the burner to extinguish the flame. 10 Early examples of these stoves are set forth in United States Letters Patent No. 421,826, granted February 18, 1890, for Caleb V. Fleetwood's "Automatic feeding device for petroleum-burners," and No. 558,643, granted April 21, 1896, for Frank R. Fennessy's "Oil-supply tank."

The present invention consists in certain novel combinations of parts hereinafter described and claimed.

25 The objects of this invention are to wholly dispense with all valves, stuffing-boxes, and piston-movements in automatic oil-stoves; to fully utilize in an automatic oil-stove the principle of the "student-lamp" oil-feed, together with a tilting movement to start or extinguish the flame and to vary its heat and intensity at will; to render the burner movable in an arc of a circle on a horizontal pivot at a distance from the burner and behind the same, whereby such movement is rendered nearly vertical; to provide for indicating and readily observing such movement at the burner; to render level or substantially level in its working position a burner movable in the arc of a circle, so as to insure a uniform distribution of oil to all parts of an annular burner or its equivalent; to provide against any obstruction of the feed-passages by water that may drip into wickless burners in such stoves; to retard for the instant the flow of oil into the burner when the tank and burner are tilted, and to provide a highly-effective mechanical device for moving the tank and burner or either of them relatively 40 to the maintained oil-level of the oil-tank in

lighting and extinguishing the flame or varying its heat and intensity, as aforesaid.

Two sheets of drawings accompany this specification as part thereof.

Figure 1 of the drawings is a small-scale 55 diagrammatic side view of an improved stove, illustrating its operation. Fig. 2 represents a vertical cross-section through the oil-tank. Fig. 3 represents a fragmentary section extending through the burner in a central longitudinal plane. Fig. 4 is an elevation of parts on the burner end of this stove, and Fig. 5 is a detail section through the valve of the oil-tank.

Like letters and numbers refer to like parts 65 in all the figures.

The improved stove comprises a suitable frame, a fragment of which is shown at A in Fig. 1, supporting by arms 1 and 2, Figs. 1 and 2, a transverse horizontal pivot B, which is thus fixedly located. The pivot is preferably tubular and provided at its ends with screw-nuts 3, Fig. 2, by which it is fastened in place; but these details are not considered material. Said pivot is embraced or, it may be, partially embraced by a foot-piece 4 at the lower end of the tubular stem 5 of an oil-supply tank C of the student-lamp type. Such tank comprises, as is customary, a removable inner tank or fount 6, having a spring-closed 70 valve 7, carried by a screw-cap 8 and provided with a protruding stem 9, which when the fount is in place keeps the valve open, as in the drawings. A burner D at the other end of the stove is preferably annular, as 75 shown, and of the "wickless" variety, having an oil-cup 10, Fig. 3, within which a "starting-ring" 11, of asbestos, provides for heating the cup and igniting the oil. Rigid pipe connections E between said tank and said burner 80 connect with said tubular stem 5 of the tank and the central neck 12 of the burner and comprise a water-trap 13, which is depressed with reference to the oil-level and serves to receive and to hold any water that may get 85 into the burner, so as to keep the same from "plugging" or obstructing the oil-passages. The depressed portion of the pipe connections serves also to retard the flow of oil from the tank C to the burner B when these parts are 90 95 100

quickly tilted. Said connections E further comprise a nose-piece 14, the "nose" *n* of which projects through a vertical slot 15 in a vertical face-plate or dial-plate F, Fig. 4, 5 fixedly attached to the frame A at the burner end of the stove, and is engaged by an index-piece or pointer 16 of L shape in side view, the upright portion of which has a hole loosely fitted to said nose *n*. The horizontal portion 10 of said index-piece is attached to the upper end of a non-rotary screw 17, which works in vertical guides 18, 19, and 20 on the face of the dial-plate F, and between said guides 19 and 20, as fixed supports, a wheel-nut 21 15 turns on the screw 17 and moves the latter, and therewith the index-piece 16, nose-piece 14, connections E, burner D, and tank C, to effect the tilting of the latter parts relative to the oil-level *o*, as represented by dotted lines 20 *t* in Fig. 1. A stop 22 limits the downward movement of the screw 17 to prevent strain on the joint between its upper end and the index-piece 16.

In addition to the substitution of an open 25 or U-shaped foot-piece at 4 in place of the sleeve form represented in the drawings any approved make of burner may be used in the improved stove, and other like modifications will suggest themselves to those skilled 30 in the art.

By the location of the pivot beneath the tank and at a distance behind the burner, as shown and described, the motion of the burner in the arc of a circle is rendered nearly vertical and sufficient in scope to facilitate indicating and observing the movement at the 35 tilting device, as in Fig. 4, the tilting and indicating devices being conveniently located at the burner end of the tilting structure and 40 beneath the burner.

By so constructing and attaching the burner that its oil-cup is level or substantially level, as shown in its normal or working position, the equal distribution of the oil within the 45 oil-cup is insured at the time when this is important, which is when the oil-cup contains the least quantity of oil required to supply the flame. Its inclination when depressed to flood the burner and when elevated to extinguish the flame is quite immaterial.

The rigid connections E serve not only for conducting the oil from the tank C to the burner D and supporting the latter, but also for conveying motion from the tilting device 55 to the tank, and in the form shown serve at the same time as an effective water-trap and flow-retarding device, as above described.

The tilting and indicating devices as a whole are conveniently carried by the dial-plate F, and owing to their loose and indirect connection with the burner are protected 60 against excessive heat. Their distinctive construction and operation as above described provide for quickly effecting the required 65 movements and for automatically holding the moving parts steady in whatever position

they may be left in by the operator, and also, in connection with the alternative open or U-shaped foot-piece at 4, for rendering the tilting structure as a whole readily removable 70 at will for any purpose.

Having thus described said improvement, I claim as my invention and desire to patent under this specification:

1. A stove comprising a fixedly-located 75 transverse horizontal pivot as a center of movement, an oil-supply tank of the student-lamp type having its maintained oil-level at an automatically-regulated distance above said pivot, an annular burner fed by said tank, 80 rigid connections between said tank and burner, and means for tilting said tank-burner and connections upon said pivot to raise or lower the burner relative to said oil-level. 85

2. In an oil-stove, the combination of a tank 90 of the student-lamp type and a burner fed by said tank, united in a rigid structure, a horizontal pivot beneath the tank on which said structure can be tilted to raise or lower the 95 burner, in the arc of a circle, with a nearly-vertical movement, and means for tilting the same located at the burner end of the structure.

3. In an oil-stove, the combination of a tank 95 of the student-lamp type and a burner fed by said tank, united in a rigid structure, a horizontal pivot beneath the tank on which said structure can be tilted to raise or lower the 100 burner, in the arc of a circle, with a nearly-vertical movement, and means for indicating such movement located at the burner end of the structure.

4. In an oil-stove, the combination with a tank of the student-lamp type of a burner fed 105 by said tank and movable on a horizontal pivot distant from the burner and behind the same, whereby such movement is rendered nearly vertical.

5. In an oil-stove, the combination with a 110 tank of the student-lamp type of a burner fed by said tank, movable up and down in the arc of a circle, and having an oil-cup which contains the greatest quantity of oil in an inclined position below its normal plane and 115 contains the least quantity of oil required to supply the flame in a substantially horizontal or level position.

6. In an oil-stove, the combination with a burner and connections of a tank of the student-lamp type, a foot-piece and a nose-piece 120 united with said tank in a rigid structure, a horizontal pivot coacting with said foot-piece, and means for tilting said structure coacting with said nose-piece. 125

7. In an oil-stove, the combination with a burner and connections of a tank of the student-lamp type having a vertical stem at bottom terminating in a foot-piece, a horizontal pivot coacting with said foot-piece, a rigid 130 connection extending from said stem between said foot-piece and the bottom of the tank, a

nose-piece at the other extremity of said connection, and a tilting device coacting with said nose-piece.

8. In an oil-stove, the combination of a tank 5 of the student-lamp type and a burner fed by said tank, united in a rigid structure, comprising a nose-piece at the burner end, a horizontal pivot on which said structure can be tilted to raise or lower the burner, and a tilting device coacting with said nose-piece.

9. In an oil-stove, the combination of a tank 15 of the student-lamp type having a vertical stem at bottom terminating in a foot-piece and a burner fed by said tank, united in a rigid structure, a horizontal pivot coacting with said foot-piece, and means for tilting said structure on said pivot to raise or lower the burner.

10. In an oil-stove, the combination with a 20 tank of the student-lamp type having a pivotal support beneath the same and a wickless burner fed by said tank of a rigid connection between the tank and burner forming the oil-feed and having a portion depressed below the oil-level to form a water-trap and a flow-retarding device, and means for tilting said tank and burner coacting with said connection at its burner end.

11. The combination, in an oil-stove, of an oil-supply tank having a maintained oil-level, 30 a burner fed by said tank, a non-rotary adjusting-screw, a wheel-nut upon said screw, a pair of fixed supports between which the nut works, an index-piece or pointer to which said screw is attached, and a dial-plate behind said pointer.

12. The combination, in an automatic oil-stove, of an oil-supply tank a burner and connections having a tilting movement and provided with a nose-piece, an index-piece or 40 pointer applied to said nose-piece, and an adjusting-screw attached to said index-piece.

13. The combination, in an automatic oil-stove, of an oil-supply tank a burner and connections having a pivotal movement and comprising a nose-piece, an index-piece applied to said nose-piece, a non-rotary adjusting-screw attached to said index-piece, a wheel-nut engaged with said screw, and vertical guides for said screw including a pair of fixed supports 45 between which said wheel-nut works.
